UNITED STATES PATENT OFFICE.

JOHN THOMSON, OF NEW YORK, AND FRANCIS A. J. FITZ GERALD, OF NIAGARA FALLS, NEW YORK, ASSIGNORS TO JOHN THOMSON PRESS COMPANY, OF JERSEY CITY, NEW JERSEY, A CORPORATION OF NEW JERSEY.

ELECTRIC ZINC-DISTILLING FURNACE.

1,219,194.

Specification of Letters Patent.

Patented Mar. 13, 1917.

Application filed June 21, 1916. Serial No. 104,838.

To all whom it may concern:

Be it known that we, JOHN THOMSON and FRANCIS A. J. FITZ GERALD, citizens of the United States, and residents, respectively, 5 of the borough of Manhattan, city of New York, county and State of New York, and of Niagara Falls, county of Niagara, State of New York, have invented certain new and useful Improvements in Electric Zinc-Distilling Furnaces, of which the following is 10 a specification, reference being made to the accompanying drawings, forming a part hereof.

This is an invention relating to the metallurgy of zinc, and it particularly pertains to 15 an apparatus for the purification of spelter containing deleterious metals, such as lead, iron and cadmium, by distillation in an electric furnace. The objects of the invention 20 are to construct an apparatus in a manner to minimize the cost of transforming metal into fume or gaseous vapor, to retain certain elements of the fume within the furnace and to then evacuate and conduct other 25 portions of the fume, viz., portions which are at the lowest permissible temperature, to any suitable means for liquid condensation, or for precipitation as dust, or for burning to an oxid.

30 In the accompanying drawings, which constitute a part of this specification there is illustrated a preferred but not necessarily an exact detail mode of realizing the invention.

35 Figure 1 is a vertical transverse center section, viewed as denoted by the arrow on line A of Figs. 2 or 3; Fig. 2 is a vertical longitudinal center section, viewed as denoted by the arrow on line B of Figs. 1 or 3; Fig. 40 3 is a top plan, the cover and several of the upper septum-plates being omitted, and Fig. 4 is a detail showing a feature of construction less clearly shown in the necessarily smaller scale of the assembled drawings.

45 The heating system of the furnace needs only be here described in so far as will incorporate it as an element in combination with the novel features of the invention. Thus, it is comprised in a suspended carbon 50 resistor, C, shown as the zig-zag type, attached by a connector, 5, for electrification

in series, when incited through the terminals, 6, 7, from the diagrammatically illustrated source of energy 8.

Beneath the resistor is a trough, or tank 55 9, which contains the bath of molten metal, as 10, usually supplied through a spout, indicated by the dotted lines, 12, Fig. 2.

In furnaces having a zig-zag type of resistor as hitherto constructed, the operation 60 and result were such that the fume flowed directly upwardly from the bath, through the zig-zag slots and around the sides of the resistor and thence through superimposed slotted or ported septums, the latter 65 acting to somewhat conserve the heat emitted by the upper surface of said resistor. But as the area of the bath was relatively large and as the rate of fume-flow was also correspondingly low or sluggish, the fume became super-heated, its temperature in fact approximating that of the resistor. However, some portions of this super-heat were dissipated by causing the fume to pass along horizontal septum-spaces 70 75 and in contact with the walls and roof of the furnace.

It will here be noted that while the temperatures at which various metals will "boil" have been rather accurately determined, as, say, the conventional figures of 930° for zinc and 1800° C. for lead, various conflicting phenomena are observable when the fume of several metals are combined, as in the instance of combining metals as 80 85 an alloy. Thus, a large volume of zinc-fume may carry with it a minor volume of lead-fume although the temperature of the resistor may not exceed 1,300° to 1,400° C. On the other hand, given two metals, that 90 having the higher fuming temperature will also condense at the higher temperature.

It has been proven in practice, as was primarily theoretically predicated, to be of the highest importance not only to avoid 95 "hot-spots" on the bath, due to the direct action of the resistor, but that the flow of fume from its surface must be uniformly distributed. In other words it is important that a constant amount of fume be emitted 100 from each square inch of the exposed surface of the bath. If not, those portions of

the bath from which fume passes off most slowly will absorb an excess of heat-units and thus become in fact hotter than other portions from which fume escapes more freely.

Again, the facility with which zinc-fume can be rapidly condensed, in large volume, is considerably a function of its temperature. Thus, if fume enters the condenser at 10 a temperature of, say, 1,300° C., about 350° must be emitted to atmosphere before the critical point is approximated, whereas if the fume enters at about 950° the initial condensing temperature may be almost immediately reached.

The foregoing premises are to be kept in mind as relates to the construction and functioning of the remaining features of the furnace now to be described.

20 The resistor and connector is incased, or boxed-in, except at the lower side, by two vertical aprons or septum-plates, 13, 14, supported on struts, 15, 16, anchored in the furnace walls, and an over-lying horizontal 25 septum, 17, which rests upon the side septums. The latter are set so as to leave vertical spaces, or flues, 18, 19, along the side walls of the furnace and also to provide spaces, or ports, 20, 21, beneath their lower 30 edges and contiguous to the space between the top of the trough and the surface of the bath. Upon the horizontal septum, 17, is preferably laid a layer of granular charcoal or petroleum coke, 22. Again, above 35 the coke is an upper septum, composed of plates, as 23, which may be supported by the furnace walls, as shown. One end of these plates is partially cut away to form a series of ports, as 24, overlying either set 40 of the vertical flues, or whichever set that is opposite from the exit to the condenser. Over the upper-septum is a large fume-chamber, P, inclosed by a relatively thin cover, formed of plates, 25, and leading 45 from the said chamber is a throat, 26, through which fume eventually passes to any suitable means for condensing, not shown but indicated by the dotted outline, J.

It will now be perceived that the fume 50 within the resistor-“boxing” is imprisoned, “dead”, serves as a blanket or envelop for the resistor, and cannot flow therefrom; the only escape for the evolved bath-fume being right and left along its surface, as along 55 rows a, thence vertically through flue 18 and the ports, as arrows c, i, also vertically through flue 19, thence horizontally along the intermediate space, R, between the horizontal septums, as arrows d, e, h, and finally 60 again vertically through the ports, 24, whereat it commingles with the fume from flue 18.

The coolest fume is that first rising from the bath, thence escaping to the side flues 65 and this, at its liberation, is probably not

over 950° C. In flowing across the bath, however, and thence up through the flues, additional heat is absorbed.

The hottest fume is that immediately in contact with the resistor and surrounding 70 boxing; which, being a gas, is perfectly transparent to the radiant heat from the resistor and also being a very poor thermal conductor gives little heat to the fume rising from the bath but prevents that fume 75 from coming in contact with the resistor, whereat it would become superheated.

No heat directly radiated from the resistor reaches the furnace side-walls, as the impingement is upon the inner surfaces of 80 its casing; hence the heat imparted to the furnace walls is largely confined to that contained in the up-flowing fume.

The areas of the side-flues and the intermediate horizontal septum chamber are to 85 be such that a relatively rapid flow of fume must occur therein.

As is well known, granular charcoal or coke is a good non-conductor of heat. Hence, this acts to insulate the septum; 90 energy is thereby conserved in the resistor. Due to the layer of granular charcoal or coke the horizontal space, R, can become a cooling chamber for the fume which passes through said space. The heat imparted to 95 the upper septum plates, 23, is largely that conveyed by the fume. The charcoal or coke, as the case may be, also serves another desirable purpose. At the starting of a “green” furnace, a certain quantity of CO, 100 or water-gas, $H_2O+C=H_2+CO$, will be formed and the charcoal or coke will serve to wash out any contained air thus preventing or minimizing the formation of ZnO.

As will be observed, the ports, 24, are located along the side of the furnace opposite from the condenser or the ports leading to the condenser; the upper fume-chamber is of large volumetric capacity, relative to the lower spaces and chambers, and the 110 primary cover is quite thin relatively to the furnace walls. In this wise, by a proper selection, and application thereon, of heat-insulating bricks, as 27, two advantageous conditions are obtained; first, a very slow displacement of the fume from this upper cooling chamber and, second, the opportunity to control, by means of the cover, the temperature of fume at its exit through the throat, as arrow m.

The consequences of the foregoing construction, and the conditions thereby ensuing, are that any lead-fume entrained with the zinc-fume is subjected both to a condensing temperature and also, which is of equal 125 importance, it is brought into physical contact with an ample coalescing surface, whereby liquefied lead is entrained within the furnace and drips back into the bath. To facilitate the flow of condensed lead, the up- 130

per surfaces of the horizontal septums may be given a slight slope, downwardly toward its ports, 24, as is shown in Fig. 1.

The greater the difference of temperature between the resistor and the bath, the higher will be the thermal efficiency. This axiomatic statement points to important contingent advantages, namely: the rate of fuming may be carried on at a rate which would not otherwise be permissible; the residuum need not be so frequently withdrawn, through the tap-opening 28, Fig. 2, as if the primary fuming of lead had to be more carefully safe-guarded, and the capacity and endurance of any given condenser is substantially enhanced.

Zinc-fume is exceedingly penetrative and effective heat insulating bricks are very porous. As a consequence, in starting up a "green" furnace, much spelter is lost by absorption, even to the extent of tons of metal. Many unsuccessful efforts have been made to minimize or avoid this. A satisfactory, simple and inexpensive solution has been found in the expedient of applying between the chamber wall or walls, as 29, and outer courses of bricks, as 30, and also beneath the bottom of the trough, relatively thin plates of molded crucible mixture (graphite and clay) or amorphous carbon, as 31, 32, of as large surface as can conveniently be manufactured, their contiguous edges being joined by a system of, or analogous to that of "ship-joints." By forming the laps of these joints at a slight angle, as 33, Fig. 4, to the axis of the faces of the plates, as also the end-joints, 34, they are thus caused, when confined by the brick-courses, to firmly interlock, while any contraction within the plates serves to tighten the laps on their bevels and any expansion also tightens by the direct pressure of the transverse abutting ends. This or any similar form of "ship-joint" can be easily molded or machined with a considerable degree of accuracy, thereby realizing a very effective barrier to the escape of both fume or liquid metal. The advantage of this barrier-sheathing is not confined to the metal primarily saved, as a furnace so provided can be more quickly put into full operation.

Various of the details, as illustrated in the drawings, may be modified without evasion of the essential functions. Thus, for example, baffle-plates may be set in the upper chamber, whereby to effect a sinuous flow of fume from the ports to the throat, and vertical flues might also be provided at either or both of the end-walls as well as at the side-walls of the furnace. So, too, under certain circumstances, as by the use of a thicker layer of granular or powdered carbon on the top of the resistor-casing, the upper septum may be omitted.

65 What is claimed is:

1. In an electric furnace, a suspended resistor embraced by an overhead horizontal and vertical side septums, so disposed within the main chamber as to provide fume-passages between the furnace walls and along the top of the horizontal septum. 70

2. In an electric distilling furnace, a suspended resistor facing a volatilizable bath, a suspended trough or casing surrounding the top and sides of the resistor, vertical uprising flues between the sides of the casing and the furnace-walls and connecting spaces beneath the lower edges of the casing, whereby vaporized products are trapped in the casing but are otherwise free to escape. 75

3. In an electric furnace, a suspended resistor whose top and sides are incased by a horizontal and two vertical septums, vertical fume-flues between the side-septums and the furnace walls and a superimposed horizontal ported septum forming a fume-chamber between it and the roof of the furnace, whereby the rising fume passes from the flues through the septum ports and thence into said chamber. 80

4. In an electric furnace, an open bottomed septum casing, suspended within the main furnace chamber, within which is a suspended resistor, and an underlying volatilizable charge, whereby the gases or fumes collected in the said septum-casing cannot be displaced. 90

5. In an electric zinc distilling furnace, a resistor casing, open at its bottom and having an overlying layer of granular carbon, such as charcoal or petroleum coke, 100

6. In an electric zinc furnace, a resistor casing surrounding the top and sides of a downwardly radiating resistor, an underlying bath, spaces beneath the lower edges of the casing and open flues between the sides of the casing and the furnace walls which communicate with the upper portion of the furnace chamber, the latter having a throat leading to a condenser. 105

7. In an electric furnace for distilling zinc, a resistor enveloped by non-displaceable fume contained in a casing open at its bottom, above a bath of metal, and having spaces below its edges and flues along its outer sides, whereby the evolved fume traverses across the lower zone of trapped fume and thence rises vertically through the flues. 115

8. An electric furnace for refining zinc-fume contaminated with lead-fume, comprised in a bath over which a resistor is suspended and enveloped by undisplaceable fume, a system of vertical uprising side flues contiguous to the furnace walls leading to over-head enlarging spaces, whereby there is a cumulative reduction in the velocity of flow and the temperature of the fume prior to its entering the condenser. 120

9. In an electric furnace, means for securing the envelopment of a resistor with un- 125

displaceable zinc-fume, means for permitting a free upward escape of evolved fumes or gases from an underlying charge and means for progressively reducing the velocity of flow and also the temperature of the volatilized matters, whereby that substance which has the highest condensing temperature will be retained within the furnace.

10. In an electric furnace, a resistor ⁵ ~~5~~ ¹⁰ ¹⁵ ¹⁵ tum-casing for enveloping the resistor with undisplaceable fume or vapor which rises from an underlying charge, said casing being mounted upon a plurality of spaced struts or supports in such manner as to provide free spaces along its lower edges and between its sides and the furnace walls, and through which the evolved vaporous products are evacuated.

11. In an electric zinc distilling furnace, a ²⁰ horizontal septum or septums disposed between the roof of the furnace and a resistor, and beneath the resistor a trough containing the charge, the said septum or septums being sloped toward a vertical flue or flues, where- ²⁵ by any condensed metal collected thereon will flow to the charge.

12. An electric zinc distilling furnace having a trough containing the charge, a resistor above the charge, a ported horizontal ³⁰ ³⁵ septum or septums above the resistor, a fume chamber above the septum or septums and an inclosing cover whose rate of heat-radiation to atmosphere is controllable, whereby to increase or decrease the temperature of the fume prior to its entering the condenser.

13. In an electric furnace, a chamber at whose bottom is a charge, a suspended radiating resistor above the charge and a suspended septum-casing within the chamber,

surrounding the top and sides of the resistor, whereby the resistor is free to directly transmit heat to the charge but is enveloped by trapped volatilized matter evolved therefrom.

14. An electric furnace having therein an ⁴⁰ open receptacle containing a charge which is being vaporized by radiant heat from an overlying resistor, means for entrapping vapor whereby to envelop the resistor and not be displaceable therefrom, and means for ⁴⁵ ⁵⁰ permitting the vapor evolved from the charge to flow horizontally along the lower portion of the trapped vapor and thence pass vertically upward through side-flues disposed along the furnace. ⁵⁵

15. An electric furnace having a radiating resistor enveloped in non-displaceable vapor directly received from an underlying open receptacle containing the charge, and means for permitting the continuously ⁶⁰ evolved vapor to freely escape along the lower zone of said envelop and thence upwardly.

This specification signed and witnessed the 14th day of June, A. D., 1916, in the city of ⁶⁵ New York, borough of Manhattan, State of New York, by—
